(57) **CLAIM**

The ornamental design for a pine straw edging device, as shown and described.

DESCRIPTION

FIG. 1 is a perspective view of a pine straw edging device of the present invention;

FIG. 2 is a front elevational view of the edging device of FIG. 1;

FIG. 3 is a rear elevational view of the edging device of FIG. 1;

FIG. 4 is a left side elevational view of the edging device of FIG. 1;

FIG. 5 is a right side elevational view of the edging device of FIG. 1;

FIG. 6 is a top plan view of the edging device of FIG. 1; and, FIG. 7 is a bottom plan view of the edging device of FIG. 1. The broken lines represent portions of the edging device and form no part of the claimed design.
